UNITED STATES PATENT OFFICE.

ANTHONY WALTER BORCYK, OF ROCHESTER, NEW YORK, ASSIGNOR TO AMERICAN PIANO COMPANY, OF NEW YORK, N. Y., A CORPORATION OF NEW JERSEY.

TREADLE AND LOWER-DOOR OPERATING MECHANISM.

1,251,958.

Specification of Letters Patent.

Patented Jan. 1, 1918.

Application filed July 27, 1916. Serial No. 111,594.

To all whom it may concern:

Be it known that I, ANTHONY WALTER BORCYK, a subject of the Emperor of Austria, now residing at Rochester, New York, 5 have invented an Improvement in Treadle and Lower-Door Operating Mechanism, of which the following is a specification.

This invention relates to foot-power player-pianos and the like, and pertains 10 more particularly to apparatus for opening and closing a door in the bottom of the instrument through which the treadles are moved into and out of operative position; the mechanism for this purpose being combined, if desired, with means for moving the 15 pumping treadles into and out of operative position.

The objects of the invention will be partly 20 obvious from the following specification and partly pointed out therein.

The invention may be readily understood by reference to one illustrative embodiment shown in the accompanying drawings, in which:

25 Figure 1 is a front elevation of playing treadles with a portion of the base of a player-piano or the like;

Fig. 2 is a detached detail showing parts 30 of the operating mechanism in different positions;

Figs. 3 and 4 are both sections upon the line 4—4 in Fig. 1; the respective figures showing different positions of the treadles; and

35 Fig. 5 is a detail section on the line 5—5 of Fig. 1.

The treadles 7, 7 are hinged to a treadle support 8 which may be provided with feet 9 preferably having rubber treads. The 40 treadles are provided with pivoted thrust bars 10 by which they are connected with a pitman 11 for operating the pumps or feeder bellows which are unnecessary to be shown.

The treadle support 8 is secured to rock- 45 ing arms 15, 15, fixed to or conveniently made integral with coaxial shafts 16, 16 journaled in any suitable manner inside the base of the player. The treadles are swung into and out of operative position upon the 50 shafts 16; the operative position, *i. e.*, when the treadles are in position to be operated for pumping, being shown in Fig. 4 and the inoperative position, *i. e.*, when the treadles are retracted into the base of the player, 55 being shown in Fig. 3.

A base panel 18, incloses the lower part of the player below the key-bed, is held in place by pins 75, 75 along the lower frame of the piano and a resilient catch 80 under the key-bed, and is readily removable from 60 the piano in the usual manner. To remove the base panel the catch 80 is raised, the top of the panel pulled forward while the pins 75 act as a fulcrum, and the panel then lifted bodily out of the instrument. It is 65 of great importance, especially in player pianos, that the base panel be easily removable to give access, for adjustment and repair, to the mechanism usually located below the key-bed.

A door-way 20 in the panel 18 permits the treadles and connected parts to be swung from within the base of the player to the operative position and back again. It is 70 preferred that when the treadles are not in operative position the door-way in the panel 75 shall be closed, and for this purpose a door 22 is provided. The door 22 has eye-pieces 23, 23 slidably mounted upon a shaft 24 which is fixed in brackets 25, 25 secured 80 to the panel 18; the door 22 sliding lengthwise the shaft 24 to close and open the door-way 20.

A single actuating means may be provided for operating the door and for moving 85 the treadles from the position shown in Fig. 3 to that shown in Fig. 4, and vice versa. For this purpose a crank arm 30 is fixed upon the shaft 16 and has pivoted to it a vertically movable rod 31 having a pivot 90 pin 32, at its upper end, engaged by a slot 33 in a crank arm 37 which is fixed to a hand-operated shaft 38. As shown in Figs. 3 and 4, the shaft 38 is journaled in brackets 95 fixed upon the bottom of the key-bed, and, at a point within easy reach of an operator seated at the instrument, the shaft 38 is provided with a handle 39 by which to rock the shaft.

When the parts are in the position shown 100 in Fig. 1, the treadles 7, 7 are in the operative position shown in Fig. 4. If the handle 39 is brought in clockwise direction from the positions shown in Figs. 1 and 4, the pivot pin 32 will bear against the outer end of the slot 33, and the rod 31 will be forced downward to rotate the shaft 16 by moving the crank arm 30 in contraclockwise direction in Fig. 4, thereby raising the treadles 7 and retracting them into the piano. This 110

- operation is accomplished by the slight movement of the handle 39 through approximately 45°, and by the co-operating action of the balancing springs 40 and 50.
- 5 Upon further movement of the handle the pivot pin will slide freely in slot 33 toward the axis of shaft 38, and thereafter a further movement of the handle 39 will have no further effect upon the treadles.
- 10 To relieve the operator from the necessity of exerting the full amount of force upon the handle 39, which may be necessary to move the treadles back and forth, an arrangement of springs is shown in the accompanying drawings which materially assist the movement of the treadles. A spring 40 (Figs. 3 and 4) is secured at one end to an eye-bolt 41 fixed upon the base of the player, and at its other end to a crank arm 42 fixed
- 15 upon the shaft 16. The spring 40 is so located and is of such length, that it exerts no material pull upon its arm 42 of the shaft 16, when the parts occupy the position shown in Fig. 3. As the treadles are moved outwardly, however, (clockwise in Fig. 3) the spring 40 begins to be tensioned from the time the arm 42 is substantially horizontal, and is thereafter increasingly tensioned until the arm 42 reaches the substantially vertical position shown in Fig. 4. The spring 40 is preferably so adjusted that this increasing tension substantially balances the increasing effective weight of the treadles as they move outwardly from the position
- 20 in which their center of gravity is substantially vertically above the shaft 16 upon which they rotate.
- A second spring 50 has its upper end secured to a stationary bracket 51 mounted on the frame of the player and its other end secured to the crank arm 42 upon shaft 16. When the parts are in the position shown in Fig. 4 the arm 42 is substantially vertical and the spring 50 is so far relaxed as to exert no material pull thereupon. The spring 50 is preferably so adjusted that it does not exert any substantial pull upon the arm 42, as the latter moves contraclockwise in Fig. 4, until the treadles have reached and passed the position in which their center of gravity stands above the shaft 16. Thereafter, however, in moving the treadles toward the position shown in Fig. 3, the arm 42 increasingly tensions the spring 50 so that the increasing effective weight of the treadles toward the end of its retracting movement, is substantially balanced by the spring 50.
- For the purposes of the specific arrangement shown in the drawings, it is desirable to utilize the same handle 39 for closing the door 22 after the treadles have been retracted into the position shown in Fig. 3. For this purpose the shaft 38 is provided with a
- 25 crank arm 60 connected by a bent link 62

with a lever 63 fulcrumed at 64 to a bracket on the bottom of the key-bed. Means are provided for releasably connecting the lever 63 with the door 22 in such manner that the door 22 will be disconnected from the lever 63 upon forward movement of the base panel 18 when it is being removed from the instrument. Such means are herein shown as a block 65 (see Fig. 5) having lugs 66 to engage the lever 63 and cause the door 22 to be moved along its supporting rod 24 upon the rotation of the handle 39. The block 65 will be readily disengaged from the lever 63 upon forward movement of the base panel 18. When the lever 63 is rocked to the left in Fig. 1 the door 22 slides to the left on its supporting rod 24 and closes the door-way 20.

When the treadles 7 are in the operative position shown in Fig. 4, their pump-operating links 10 extend through the door-way 20; hence at such times the door is desired to remain open. Likewise the door is preferred to remain open until the treadles have been sufficiently retracted into the interior 90 of the base to avoid interference with the closing door. This is provided for in the illustrative means for closing the door by the handle 39.

When the parts are in the position shown in Fig. 1, the door 22 stands wide open and the treadles stand in the operative position of Fig. 4. The handle 39 being then moved clockwise, the bar 31 is forced downwardly to rock the treadles toward inoperative position. This downward movement of the rod 31 begins almost immediately the handle 39 is moved clockwise, but the door closing crank arm 60 is so positioned on the shaft 38 that during the first part of the movement of the handle 39 and the retracting movement of the treadles, the lever 63 is not materially moved. When, however, the rod 31 has been moved downwardly far enough to substantially complete the retracting 110 movement of the treadles, the lever 63 begins to move clockwise in Fig. 1 to start the closing of the door 22. During this treadle retracting and door closing movement, the door preferably has the latter part of its 115 movement after the retracted treadles have substantially come to rest. Therefore, the treadle operating mechanism is so constructed that when the rod 31 has positively thrown the treadles beyond the position 120 where their center of gravity stands above the shaft 16, the pivot pin 32 will slide along the slot 33, whereupon the shaft 38 may be moved still farther to move the parts into the position shown in Figs. 2 and 3; wherein 125 the door 22 is completely closed to cover the treadles and restore the finished panel appearance of the base panel 18.

On the door-opening and treadle-advancing movement, the handle 39 is rocked con-

traclockwise from the position shown in Fig. 2 thereby starting to open the door and at least partially completing that opening, before the pivot pin 32 engages the inner end 5 of the slot 33 to start the treadle-advancing movement. Thus the door is out of the way to permit the treadles to be thrown out through the door-way 20 during the latter part of the contraclockwise movement of the 10 handle 39.

It is to be understood that the invention is not limited to the precise construction, organization and mode of operation shown in the drawings and described above for 15 illustration. On the contrary, the invention may be variously embodied and the illustrative construction may be variously modified within the proper scope of the subjoined claims.

20 I claim as my invention:

1. In a musical instrument, the combination of a removable base panel having a door-way; a door connected to said panel and removable therewith; door operating 25 means connected to another part of the instrument, and two interengaging members connected respectively to said door and said door operating means, one of said members having a recess for engagement with the 30 other.

2. In a musical instrument, the combination of a removable base panel having a door-way; a door connected to said panel and removable therewith; door operating 35 means connected to another part of the instrument; and means on said door providing a recess to be internally engaged by a part of said door operating means and arranged for disengagement by forward movement of 40 the removable base panel.

3. In a musical instrument, the combination of a removable base panel having a door-way; a door slidably mounted upon 45 said base panel to close the doorway and removable therewith; door operating means

mounted upon another part of the instrument and including a depending lever to swing in a plane parallel to that of the door; and means projecting from the door at right angles to the plane of said depending lever 50 to engage the same on either side thereof.

4. In a musical instrument, the combination of a removable base panel having a doorway; a door slidably mounted upon said base panel to close the doorway and removable therewith; door operating means mounted upon another part of the instrument and including a depending lever to swing in a plane parallel to that of the door; and a pair of lugs upon said door to 60 engage the lever only when the door and base panel are in their normal planes.

5. In a musical instrument, the combination of treadles movable between operative and inoperative positions; a door mounted 65 upon a removable base panel to inclose the treadles when in inoperative position; a control lever mounted upon another part of the instrument and adapted to move the door and treadles respectively in sequence; and 70 two interengaging members connected respectively to said door and to said door operating means, one of said members having a recess engaged by the other.

6. In a musical instrument, the combination of treadles movable between operative and inoperative positions; a door to inclose the treadles in inoperative position; a rock shaft for moving said door and treadles; a bent link connecting a crank arm upon said 80 shaft with a door moving member; and a slotted crank arm connecting said shaft with a treadle operating member, whereby the door and treadles are moved in sequence by a continuous movement of the rock shaft. 85

In testimony whereof, I have signed my name to this specification this 22d day of July, 1916.

ANTHONY WALTER BORCYK.
